UNITED STATES PATENT OFFICE.

WILLIAM H. HOLLOWAY, OF DENVER, COLORADO.

SYSTEM AND APPARATUS FOR THE CONTROL OF ELECTRIC-CIRCUIT BREAKERS.

1,310,081.

Specification of Letters Patent.

Patented July 15, 1919.

Application filed December 7, 1916. Serial No. 135,597.

To all whom it may concern:

Be it known that I, WILLIAM H. HOLLOWAY, a citizen of the United States, residing at Denver, in the county of Denver and State of Colorado, have invented certain new and useful Improvements in Systems and Apparatus for the Control of Electric-Circuit Breakers, of which the following is a specification.

10 This invention relates to a system and apparatus for the control of electric circuit-breakers and its primary object is to provide in one or more circuits which are independent of the circuit controlled by a circuit-breaker, apparatus adapted to actuate one circuit-breaker singly or a series of circuit-breakers consecutively for their movement to a circuit opening position.

With the above object in view, my invention 20 comprises a system of electrical devices and circuits by the use of which a circuit-breaker may be actuated to open a circuit in which it is connected from one or more distant points, or by means of which circuit-breakers used to control the circuits of a 25 number of motors working in step to drive a succession of machines employed in the operation of certain processes, are successively and automatically actuated to break 30 their respective circuits after one of the circuit-breakers of the series has been operated to open the circuit it controls either by a manual operation or by the action of an electro-magnetic overload attachment.

35 Still further objects of my invention reside in providing in connection with a system of the character outlined above, an electric alarm which automatically calls the attention of the operator or operators to a 40 break in one of the motor circuits, and in other arrangements for controlling the operation of one or more circuit-breakers, all of which will be fully disclosed in the course 45 of the following description with reference to the accompanying drawings in which—

Figure 1, designates a face view of a circuit-breaker to which my invention is applied,

Fig. 2, a section taken along the line 2—2, 50 Fig. 1, and

Figs. 3, 4, 5 and 6 different systems of electric circuits in which the elements of my invention are included for obtaining the results outlined above and hereinafter to be 55 more specifically described.

Referring to the drawings by numeral

reference characters which in the several views designate corresponding parts; my invention has been shown as applied to circuit-breakers 50 of conventional construction such as illustrated in Figs. 1 and 2 in which a stationary contact-member 2 and a movable contact member 3 are connected in opposite sides of the electric circuit controlled by a circuit-breaker of which they 65 form part.

The movable contact member is pivoted as at 4 for movement to and from the stationary member, a toggle movement 5 operates to move the contact member 3 into engagement with its correlative against the action of a spring 6 which tends to separate the members, and a latch 7 locks the moving contact-member in its adjusted position by connection with a part of the toggle. 75

In the construction shown in the drawings, two units each constructed as herein-before described, are provided to control opposite sides of one circuit and an automatic device is placed in operative adjacency to said units for their simultaneous actuation by an overload of the circuit in which they are connected. 80

The overload circuit breaking device consists of an electro-magnetic coil 8 connected 85 in the circuit of the two circuit breakers, and an armature 9 which when attracted to the core of the coil by its magnetization in case of an overload, engages the latches 7 of the circuit breakers and thereby releases 90 the toggles 5 to separate the movable contact members 3 from the respective stationary members 2 by action of the springs 6.

The circuit-breakers herein shown and described are merely illustrative of the class 95 of electrical devices to which my invention may be effectually applied either separately or in conjunction with an overload attachment of suitable construction.

My invention includes two mechanical elements which coöperate for the actuation of one circuit breaker by the movement of another to a position in which the circuit it controls is opened. 100

One of these elements, designated in its 105 entirety by the reference numeral 10, consists of a solenoid 12 and a fulcrumed lever 13 which rests upon the upper end of the longitudinally moving solenoid core 14 to be lifted by action thereof when the windings of the coil in which the core has its 110 movement, are energized.

The lever 13 is positioned to actuatively engage the latch 7 of one of the circuit breakers and thereby release the toggle of the same and cause the movable contact

5 member to be separated from the stationary member by the action of the spring 6.

When the element 10 is applied to a circuit-breaker associated with an overload actuating device, the free end of the lever is 10 placed between the latch and the part of the armature of the overload coil, adapted to engage the same, so that the two actuating devices may work conjointly or independently without interfering with each other.

15 The other mechanical element of my invention which in its entirety has been designated by the reference character 15, comprises a circuit-breaker which is composed of a plunger 16 loosely extending 20 through a sleeve 17 of nonconducting material and carrying a head 18 which normally engages two resilient contacts 19 secured at an end of the sleeve.

A spring 20 disposed within the sleeve, is 25 provided to move the plunger to the position in which its head engages the contacts to close a circuit in which said contacts are connected.

The circuit-breaking element 15 of my 30 invention is disposed with relation to a circuit breaker of the hereinbefore described construction so that the movable contact-member thereof when placed in engagement with the stationary contact member pushes 35 the plunger 16 outwardly to separate its head from the contacts 19 against the action of the spring 20.

Having thus described the construction of the mechanical elements of my invention I 40 will now proceed to describe the electric circuits with which they are associated in a system to perform the functions hereinbefore referred to.

The system illustrated in Fig. 3 is designed 45 to effect the actuation of any one of a series of circuit-breakers from one or more distant points, and the subsequent automatic actuation of all or a part of the remaining circuit breakers of the series.

50 This system is particularly adapted for use in a plant in which a process is carried on by the coöperative actions of a succession of electrically operated units.

In a plant of this type in which each unit 55 performs a distinctive step in the process and the material to be worked is automatically fed from one unit to another, it is obviously essential that if the operation of one of the units is discontinued, the other 60 units of the series or at least those following the inoperative unit, should also be brought to rest.

Referring to Fig. 3 of the drawings, the 65 solenoid coils of the actuating elements 10 of the invention, operatively associated with

a series of circuit breakers A, B, C, D and E, are connected in a controlling circuit which is manually closed and opened by switches of the push-button type.

The controlling circuit includes in connection with a source of electricity 21, two line conductors 22 and 23 connected by a plurality of cross-wires 24 by which the solenoid coils 12 are connected in multiple in the circuit and which are individually controlled by the before-mentioned switches which in the drawing are designated by the numerals 25.

An electric alarm provided to call attention to a break in any one of the circuits 80 controlled by the circuit breakers is disposed in a separate electric circuit which comprises in connection with a source of electricity 26, two conductors 27 and 28 between which the alarm 29 is connected. 85

A break in the conductor 28 is bridged by a lever 30 connected with the armature of the solenoid 31 which by means of conductors 32 and 33 is connected at opposite sides of a break in the line conductor 22 of the 90 controlling circuit.

The circuit-breaking elements 15 applied to the series of circuit-breakers are disposed in multiple in a secondary circuit which in connection with a separate battery 34 includes a line-wire 35, the before-mentioned line-conductor 22 of the controlling circuit and conductors 36 which are connected between these two line conductors. 95

The several conductors 36 each include 100 one of the circuit-breaking elements of my invention and the solenoid of the actuating element associated with the circuit breaker of the series, next following that to which the circuit-breaking element is applied.

The circuits so far described are adapted to cause the automatic actuation of the circuit-breakers of the series following that which is actuated by closing the circuit-breaker through the medium of the respective switches 25, and if it is desired to actuate every circuit breaker of the series by the opening movement of one, a cross wire in which the circuit breaking element 15 associated with the last circuit-breaker E 115 of the series is connected, includes the solenoid coil 12 of the actuating element associated with the first circuit-breaker A of the series.

In the operation of the system any one of 120 the circuit-breakers may be separately actuated to break the circuit it controls by closing the controlling circuit by means of the respective switch 25.

The energization of the solenoid coil 125 causes the lever 13 to be moved in engagement with the latch 7 of the respective circuit breaker which in consequence releases the toggle of the same and causes the spring 6 to return the moving contact-member 3 to 130

the position in which it is separated from the stationary contact-member 2.

The movement of the contact-member 3 releases the plunger 16 of the circuit-breaking element 15 applied to the same circuit-breaker of the series, with the result that its head 18 is moved into engagement with the contacts 19 and closes the secondary circuit through the cross-wire 36 in which a 10 solenoid coil 12 of the actuating element applied at the next following circuit-breaker of the series is included.

The energization of the second solenoid coil 12 actuates the respective circuit breaker 15 which is moved to its circuit-opening position and thereby compels the respective circuit-breaking element 15 to close the secondary circuit through the conductor 36 in which the solenoid coil 12 of the next following circuit-breaker is connected and in this manner all the circuit-breakers of the series following that initially opened will be actuated in succession to open the circuits which they control.

25 When the last circuit-breaker of the series is provided with a circuit-breaking element 15 connected in series with the solenoid coil 12 of the actuating element of the first circuit-breaker of the series, the successive 30 actuation of the circuit-breakers is continued until every circuit-breaker of the series is placed in an open position.

Premising for example, that the switch 25 corresponding with the solenoid coil 12 of the third circuit-breaker C of the series is operated, a circuit is completed which beginning at the source of electricity 21 includes the line-conductor 23, the cross-wire 24 in which the solenoid-coil 12 of the element associated with the circuit-breaker C 40 is included, and the line-wire 22 which connects with the opposite pole of the battery.

The closing of the controlling circuit as outlined, also energizes the solenoid 31 of the circuit-breaker which controls the alarm circuit and causes the armature of the solenoid to close the circuit and thereby produce a flow of current from the battery 26 through the wire 27, the alarm 29 and the 50 wire 28 which connects with the opposite pole of the battery.

The alarm is thus sounded as soon as any one of the elements 10 is energized by means of its respective switch 25, thereby calling 55 the attention of the operator or operators to any interruption in the operation of the plant.

The opening movement of the contact-member 3 of the circuit-breaker by the energization of the solenoid coil of the respective actuating element, compels the circuit-breaking element of the same circuit-breaker, to close a circuit in which the solenoid of the actuating element of the next following 60 circuit-breaker is connected, the path of the

current through said circuit extending from the source of electricity 34 through the line conductor 35, the conductor 36 controlled by the circuit-breaking element associated with the circuit-breaker C and in which the solenoid coil of the next following circuit-breaker D is included, and the line conductor 22 which connects with the opposite pole of the source of electricity.

When the last circuit-breaker E of the series has been opened in this manner, the actuation of the respective circuit breaking element 15 closes a circuit including the solenoid coil 12 of the actuating element connected with the first circuit-breaker A of the series as follows: beginning at the battery 34 the line-wire 35, the conductor 36 controlled by the circuit breaking element of the circuit breaker E and including the coil 12 of the actuating element connected with the circuit breaker A and the line-wire 22 which connects with the opposite pole of the battery.

It will be understood that by providing a line-wire common to the primary circuit controlled by the switches 25 and the subordinate circuit controlled by the circuit-breaking elements 15, the solenoid-coils 12 are operatively placed in both circuits, and that the use of two separate batteries is essential to provide the current flow required for the actuation of all the electrical devices included in the system.

It will furthermore be observed that any number of switches 25 may be arranged in multiple in the cross wires of the primary circuit and that in consequence the circuits controlled by the circuit-breakers may be opened at any one of an unlimited number of distant points.

In the system illustrated in Fig. 4 my invention has been applied to automatic circuit-breakers of a series of co-operative electrical devices comprised in a plant. In this system the primary circuit included in the other system is eliminated and the only circuit utilized is that which in the first-described system was subordinate to the other.

When the current in the circuit controlled by one of the circuit-breakers attains too high a value, the energization of the respective overload coil 8 causes the circuit to be opened by a movement of the movable contact-members of the circuit-breakers after the toggles of the same have been released by the engagement of the armature of the overload solenoid with the latches 7.

The circuit-breaking element 15 associated with the opened circuit-breaker is in consequence moved to its circuit-closing position as before, and the solenoid 12 of the actuating element of the next following circuit-breaker which is in series with the closed circuit-breaking element is energized to open the respective circuit-breaker by the engage- 125 130

ment of the lever 13 with the latch which holds the toggle of one of its movable contact members.

The opening of the last-mentioned circuit-breaker energizes the solenoid-coil of the actuating element of the next following circuit-breaker, and the entire number of circuit-breakers following that which was initially opened, are thus successively actuated to interrupt the circuits they respectively control.

If it is desired to open every circuit-breaker of the series by the actuation of one through the medium of its overload solenoid, 15 the circuit-breaking element 15 of the last circuit-breaker of the series is, as in the first-described system, connected in series with the solenoid coil 12 of the actuating element of the first circuit-breaker of the series, by 20 means of the conductor 36.

Inasmuch as the path of the current in the system shown in Fig. 4 is identical to that of the system illustrated in Fig. 3, no further description of the circuits is necessary.

My improved system and apparatus may be utilized to advantage to control a single circuit breaker from one or more distant points as is shown in Fig. 5 of the drawings 30 in which one or more switches 25 are connected in multiple in a circuit which in connection with a battery 37 includes two line conductors 38 and 39 in one of which the solenoid coil 12 of the actuating element 10 35 is connected.

The automatic circuit-breaking element 15 may in this case be eliminated or it may be used to close an alarm-circuit similar to that shown in Fig. 3, and cause the continuous 40 sounding of the alarm while the circuit-breaker is in the circuit-opening condition.

By operating one of the switches 25, a circuit is completed as follows: commencing at the battery 37 the line conductor 39, the 45 cross-wires closed by the switch 25 and the line-conductor 38 in which the solenoid coil 12 of the element 10 is included and which connects with the opposite pole of the battery.

50 In case the alarm circuit is utilized in the above-mentioned manner, the automatic circuit-breaking element actuated by movement of the movable contact member of the circuit breaker, closes a shunt 40 of the 55 solenoid circuit which includes the coil of the solenoid 31 which closes the alarm-circuit.

In the system illustrated in Fig. 6, my invention has been applied to control the opening-movement of either one of two circuit-breakers by a similar movement of the other.

The primary circuit in this system includes in connection with the battery 21, the 65 two line conductors 23 and 22 which are

individually controlled by the switches 25 and in which the solenoid-coils 12 of the actuating elements are included.

The secondary circuit includes as before, in connection with the battery 34, the line conductor 22 of the controlling circuit, a second line-conductor 35 and wires 36 by which the automatic circuit-breaking element associated with each circuit-breaker is connected in a series with the solenoid of the actuating element of the other circuit-breaker.

If the circuit-breaker at the left-hand side of the drawing is closed by energization of the respective actuating element when the controlling circuit has been closed by means of the respective switch 25 and the corresponding automatic circuit-breaking element is at the same time actuated to close the circuit it controls, the solenoid coil of the actuating element of the other circuit-breaker 85 is energized by a flow of current along a path which commencing at the battery 34 includes the conductor 35, the conductor 36 in which the circuit-breaking element 15 of the first circuit-breaker is connected, the coil 12 of the actuating element associated with the second circuit-breaker, and the conductor 22 which connects with the opposite pole of the battery and is common to both circuits.

When the circuit of the actuating element 95 associated with the circuit-breaker at the right-hand side of the drawing is closed by means of its switch 25, said circuit-breaker is moved to its circuit-opening position by the lever of the actuating element, 100 the corresponding automatic circuit-breaking element is operated to close the circuit in which it is included and the solenoid of the actuating element connected with the other circuit-breaker is energized by a flow 105 of current along a path which beginning at the battery 34 includes the before-mentioned conductor 35, the conductor 36 including the circuit-breaking element connected with the initially actuated circuit-breaker, the coil 12 110 of the actuating element of the other circuit-breaker, and the wire 22 which connects with the other pole of the battery.

Fig. 6 also illustrates the method of opening by means of my invention, both sides 115 of the circuit simultaneously by the synchronous actuation of the movable contact-members of a duplex circuit-breaker of the construction shown in Fig. 1, through the intermediary of two actuating elements connected in series in the same line wire and installed in operative relation to the two units of the circuit-breaker.

It will be observed that in each system for the operation of one or more circuit-breakers of a series by the initial actuation of any one circuit-breaker of the same series either by means of a manually closed switch or through the medium of an overload coil, there are employed in connection 130

with each circuit-breaker, with the possible exception of the first and last one of the series, two coöperative elements, to wit,— an actuating element which automatically 5 opens the circuit-breaker and a circuit-breaking element which is actuated by the movement of the circuit-breaker to close a circuit in which it is connected.

In each system, the automatic circuit-breaking element of each circuit-breaker is 10 in series in the circuit with the actuating element of the next succeeding one and if so desired the circuit breaking element of the last circuit-breaker of the series is placed in 15 a circuit in series with the actuating element of the first circuit-breaker of the series whereby to produce a succession of operations which beginning at any one circuit-breaker of a series includes all the other circuit-breakers of the same. 20

It will be understood by those versed in the art to which my invention appertains that the systems as hereinbefore described, may be installed and operated at a very low cost, 25 principally by reason of the fact that the entire system operates independently of the circuits controlled by the circuit breakers and thus permits of the use of a current of very low voltage.

30 In the use of the systems including the primary or controlling circuits, any number of switches may be employed to control the operation of the circuit-breakers of a series from an unlimited number of different 35 points and by using in connection with the system, an alarm circuit as shown in the drawings, the operators of a plant are immediately informed of any interruption in the operation of the series of units which 40 operate in the process in which the plant is used.

Inasmuch as the system of electrical connections included in the invention is completely insulated from the circuits of the 45 circuit-breakers to which the system is applied, all danger of short circuiting is eliminated while the low voltage of the circuits in the system, renders its installation safe in all places and under all conditions.

50 It will furthermore be understood that while the systems shown in the drawings and hereinabove described, provide for opening the circuit-breakers of a series following that which was opened either by 55 means of one of the switches 25 or by the action of the overload solenoid, the order of the electrical connections may be reversed to open the circuit breakers of the series preceding that initially opened.

60 Having thus described my invention what I claim and desire to secure by Letters-Patent is:

1. The combination with a circuit-breaker including a moving contact-member, a latch 65 for holding said member in its circuit-

closing position, and an electro-magnetic appliance adapted to actuate said latch by an overload of current in the circuit controlled by the circuit-breaker, of a circuit independent of that controlled by the circuit-breaker, a solenoid connected in said circuit, a switch in the same, and a lever mounted with relation to the latch and the moving parts of the solenoid and the overload appliance to be moved into impellent 70 engagement with said latch by either the energization of the solenoid or the operation of said appliance.

2. In combination, two circuit-breakers, two normally open circuits separate from 80 those controlled by said circuit-breakers, electro-magnetic actuating-elements connected in both said circuits and adapted to respectively effect an opening-movement of said circuit-breakers, means for closing 85 either circuit, and circuit-breaking elements adapted to be held in a circuit-opening position by the circuit-breakers in their circuit-closing position and to move to a circuit-closing position when the respective 90 circuit-breakers move to their circuit-opening position, the circuit-breaking element of each circuit-breaker being connected in one of said circuits in series with the actuating element of the other circuit-breaker. 95

3. In combination, a succession of circuit-breakers, circuits separate from those controlled by said circuit-breakers, coöperative actuating and actuated elements in said circuits to effect an opening-movement of any 100 one of said circuit-breakers and to effect an opening-movement of any circuit-breaker by the opening-movement of the immediately preceding one, and switches connected in one of said circuits so as to actuate any actuating element separate from the others.

4. In combination, a succession of circuit-breakers, a circuit separate from those controlled by said circuit-breakers, coöperative 110 elements in said circuit, to effect an opening movement of any circuit-breaker by the opening movement of the immediately preceding one, and means to initially effect an opening movement of any one of 115 said circuit-breakers.

5. In combination, a succession of circuit-breakers, a circuit separate from those controlled by said circuit-breakers, coöperative elements in said circuit, to effect an opening 120 movement of any circuit-breaker by the opening movement of the immediately preceding one, and means to initially effect an opening movement of one of said circuit-breakers.

6. In combination, a succession of circuit-breakers, means associated therewith for effecting their opening movement by an overload of current in the circuits they control, a circuit separate from those con- 130

trolled by said circuit-breakers, and coöperative elements in said circuit, to effect an opening movement of any circuit-breaker by the opening movement of the immediately preceding one.

7. In combination with a series of circuit-breakers, a corresponding series of electro-magnetic trips adapted to separately open the same, a circuit, switches in said circuit respectively in series with said trips, a second circuit, and normally open circuit-controlling devices associated with said circuit-breakers to be separately controlled by the movement thereof and each connected in said second circuit in series with the trip of the circuit breaker immediately succeeding that with which it is associated.

8. In combination with a series of circuit-breakers, a corresponding series of electro-magnetic trips adapted to separately open the same, a circuit, switches in said circuit respectively in series with said trips, a second circuit, and normally open circuit-controlling devices held in a circuit-opening position by the circuit-breakers in their

circuit-closing position and adapted to move to a circuit-closing position by the movement of the respective circuit-breakers to a circuit-opening position, said devices being connected in said second circuit each in series with the trip of the circuit breaker immediately succeeding that with which it is associated.

9. In combination with a series of circuit-breakers, a corresponding series of electro-magnetic trips adapted to separately open the same, a circuit for said trips, a second circuit, and normally open circuit-controlling devices associated with said circuit-breakers to be separately controlled by the movement thereof and each connected in said second circuit in series with the trip of the circuit-breaker immediately succeeding that with which it is associated.

In testimony whereof I have affixed my signature in presence of two witnesses.
